DESIGN FOR A SOUND ON FILM MOTION PICTURE PROJECTOR

Abraham Shapiro, Chicago, Ill., assignor to Universal Stamping & Mfg. Co., Chicago, Ill., a corporation of Illinois

Application February 16, 1939, Serial No. 83,022

Term of patent 7 years

To all whom it may concern:

Be it known that I, Abraham Shapiro, a citizen of the United States, residing at Chicago, in the county of Cook and State of Illinois, have invented a new, original, and ornamental Design for a Sound on Film Motion Picture Projector, of which the following is a specification, reference being had to the accompanying drawings, forming part thereof.

Figure 1 is a rear elevation of a projector embodying my new design.

Figure 2 is a side elevation taken from the right of Figure 1.

Figure 3 is a front elevation of the projector.

Figure 4 is a side elevation taken from the right of Figure 3.

I claim:

The ornamental design for a sound on film motion picture projector, substantially as shown.

ABRAHAM SHAPIRO.
